UNITED STATES PATENT OFFICE.

ROBERT BAUCH, OF ROCKFORD, ILLINOIS.

SECTIONAL BOOKCASE.

SPECIFICATION forming part of Letters Patent No. 746,915, dated December 15, 1903.

Application filed April 10, 1902. Serial No. 102,190. (No model.)

To all whom it may concern:

Be it known that I, ROBERT BAUCH, a citizen of the United States, residing at Rockford, in the county of Winnebago and State of Illinois, have invented certain new and useful Improvements in Knockdown Sectional Bookcases, of which the following is a specification.

One of the objects of this invention is the production of a sectional bookcase, certain of the sectional units of which case may be taken apart for shipment or storage.

A further object of this invention is the production of a means for holding the end pieces of the sections securely in vertical series.

A further object of the invention is the production of a means for securing in position the shelves between adjacent sections, which shelves constitute the top of one section and the bottom of the next higher section, and in the combination of the securing means for the end sections with the securing means for said shelves.

A further object of this invention is the production of a means for permitting the ready insertion or withdrawal of the door of any section from its position in said section.

A further object of this invention is the production of a means for retracting the door when the same is opened and for holding said door tightly shut when it is closed.

In the accompanying drawings, Figure 1 is a longitudinal vertical section through a bookcase made up of a base, a top, and three intermediate knockdown sections. Fig. 2 is a transverse vertical sectional view through such a case. Fig. 3 is a perspective view illustrating the means employed for securing the end sections in vertical series, also for securing in place the partitions or shelves. Fig. 4 is a plan view showing the rear side of a door for closing the forward side of one of the sectional units of the bookcase. Fig. 5 is an enlarged detail view showing in vertical section the joint between the end members of the case, the shelf being in dotted lines. Fig. 6 is a section on dotted line 6 6 of Fig. 5. Fig. 7 is a fragmental under side view of the shelf. Fig. 8 is a side view of one of the guides for the door of the bookcase. Fig. 9 is a frag-

mental view showing the means of securing the retracting-spring to the back panel of each section. Fig. 10 is a sectional view on dotted line 10 10 of Fig. 11, showing the position of the spring when the door is closed. Fig. 11 is a transverse vertical section on dotted line 11 11 of Fig. 10, showing the door closed. Fig. 12 is a similar view showing the position of the parts when the door is open. Figs. 13, 14, and 15 illustrate a modified means for securing the end pieces in vertical series and for supporting the partitions or shelves, Fig. 13 representing a transverse vertical section through a case embodying said modified form of my invention, Fig. 14 a longitudinal vertical section on dotted line 14 14 of Fig. 13, and Fig. 15 in perspective the parts that meet to form the joint between the end sections of the units and the partitions or shelves between said units.

In the construction of a bookcase embodying my invention I provide a base-section A, comprising the front wall A', the end pieces A², provided near their rear edges with the grooves A³ and the back panel A⁴, adapted to lie within said grooves.

The top section B comprises a front B', end pieces B², having grooves B³ near their rear edges, a back panel B⁴ lying within said grooves, and a top B⁵.

The intermediate or book sections C each comprise a shelf C', having a dovetail C² at each of its ends and a groove C³ near its rear edge on both its upper and its lower face. On its lower side and at each end thereof it also has a semicylindrical pocket C⁴, extending transversely through the lower part of the dovetail C². Each book-section further comprises a door C⁵, two end pieces C⁶, and a back panel C⁷. The two end pieces C⁶ have horizontal grooves C⁸ for receiving rollers C⁹ and C¹⁰, upon which the door C⁵ is pivotally mounted, and at their forward ends the grooves C⁸ are provided with pockets C¹¹, into which said rollers drop when the door is in its vertical or normal position. To provide for the ready removal of the door, the roller C⁹ is rotatably mounted at the free end of a leaf-spring C¹², which spring is secured to one edge of the door and at its free end overlies a

mortise cut into the door-frame. The inner side of the door-frame is provided with two hooks C¹³, forming the attaching means for the retracting-spring, to be hereinafter described. Near their rear edges the end pieces C⁶ are grooved vertically to receive the back panel C⁷ and at their bottom edges on their outer faces are provided with the cleat C¹⁴ to hide the joint between vertically-adjacent end pieces. To aid in guiding the door in its horizontal sliding movement in the upper part of the book-section, I provide two guides C¹⁵, in this instance formed from wire, one of which guides is secured to each end piece 15 near the forward edge of said end pieces on its inner face and at a point directly beneath the groove C⁸. The point of the wire forming the guide C¹⁵ is driven into the body of the end piece C⁶, and its looped end C¹⁶, elongated to act as a runner or shoe, enters the groove C¹⁷, formed in the inner face of the door-frame near each end of the door C⁵. The strip of material remaining above the groove C⁸ is strengthened by driving the pins 20 C¹⁸ into suitable openings formed in the end pieces C⁶.

The joint between the end piece A² of the base-section A and the end piece C⁶ of the book-section C and between the end pieces of 25 the book-section and the end piece B² of the top section B is a modified tongue-and-groove connection. It comprises an upwardly-extending flange D on the (relatively) lower end piece, and a groove D', formed between two flanges D² and D³ of the next higher end piece. The flange D² rests upon a shoulder D⁴, formed on the lower member, and the lower end of the flange D³ is undercut to correspond with an undercut shoulder D⁵ near the upper edge 30 of the lower member, said undercut flange and shoulder forming between them an undercut groove D⁶, adapted to receive the dovetail C⁸ at the end of the shelf C'. Near the middle of the undercut shoulder D⁵, I insert 35 into a suitable opening in the end piece a pin D⁷, the upper semicylindrical side of which pin is adapted to coincide with and lie within the pocket C⁴ in the under side of the shelf C', the purpose of the pin and pocket being 40 to hold the shelf C' in its proper position. To align the end pieces, a similar pin D⁸ is provided in the groove D' of the (relatively) upper end piece and a notch D⁹, formed in the flange D of the adjacent lower end piece. 45 A retracting-spring E, having eyes E' at its ends and an offset bend E² near its middle, is secured to the back panel C⁷ by means of the bracket E³. The eyes E' are connected with the hooks C¹³ by means of the flexible loops 50 E⁴ of cord or other suitable material. The offset bend at the center of the spring E prevents it from endwise movement and holds it from turning. When the door is closed, the spring E is flexed, and the tendency of said 55 spring is to hold the door tightly shut, inasmuch as the hooks C¹³, forming the attach-

ment between the door and the spring, are below the pivotal center of the door. When the door is raised into horizontal position, the pull of the spring is directly parallel with the grooves C⁸, in which the rollers C⁹ and C¹⁰, upon which the door is mounted, are intended to run.

In the modification shown in Figs. 13, 14, and 15 the shelf F is provided in its end with 75 an undercut groove F' to receive the dovetail rib F² of a casting F³, the flanges F⁴ of which casting are adapted to lie in the grooves F⁵ and F⁶ in the coinciding faces of adjacent 80 end pieces.

In assembling the parts of this bookcase a shelf C' is laid upon the base A, end pieces C⁶ then put in place, a back panel C⁷ slid into the grooves in the end pieces and the groove C⁸, and a shelf C' put in position. A 85 second book-section is assembled when two more end pieces are set up, another back panel slid into the grooves in the end pieces and the groove C⁸, and another shelf added. The case is thus erected to the desired height, 90 when the top B is put bodily in position. The doors are hung by depressing the spring C¹², placing the supporting-rollers C⁹ and C¹⁰ at the ends of the door into the grooves C⁸ in the inner faces of the end pieces C⁶, and 95 releasing the spring C¹². The retracting-spring E is then connected with the door by means of the flexible loops E⁴. The retracting-spring E holds the door normally tightly closed. When the door is raised into 100 horizontal position, the spring slides it inward in the upper part of the section, the rollers C⁹ and C¹⁰ traveling in the grooves C⁸ and the guide-shoes C¹⁶ in the grooves C¹⁷ in the door-frame. The retracting-spring E pulls equally 105 upon opposite ends of the door, thus moving it evenly and smoothly within the grooves C⁸ and obviating a binding of said door within 110 said grooves caused by one end of the door moving in advance of the other end. When 115 the door is being raised into a horizontal position, its rear edge strikes against the guides C¹⁵, raising the rollers C⁹ and C¹⁰ from the pockets C¹¹ at the forward end of the grooves C⁸. In ordinary use the door is not raised to 120 its upper limit, and the rollers remain normally in said pockets.

In packing my improved case for shipment or storage all parts except the base A and the top B are separated into their elements and 125 laid flat. The parts of the top and the base are fixed rigidly together.

It is clear that the lower shelf C' might be formed rigid with the base A, that the shelf C', which is placed upon the upper end of the 130 uppermost end pieces C⁶, might be made a part of the top B, that the door C⁵ might be wholly omitted, that many changes in the form of joint between adjacent end pieces and between the end pieces and the base and 135 the top might be made, that modifications of the joint for connecting the shelf with the

end pieces, whereby said shelf is separate and the case is bound together, might also be made, and that various other changes in the arrangement of the parts and in the details 5 of construction might also be made without departing from the scope and spirit of my invention, wherefore I wish to have it understood that I do not intend to limit myself to the exact form and arrangement of parts 10 herein shown and described, but consider the construction shown herein merely one of several that embody my said invention as fully as the form and arrangement herein set forth.

I claim as my invention—

15 1. In a sectional bookcase, in combination, a section comprising two end pieces; and a superposed section comprising two end pieces, a shelf having dovetail ends, and a back panel, each of said parts being freely separable from 20 all the others, the end pieces at each side of the bookcase being connected by a tongue-and-groove joint, which joint also provides an undercut channel for receiving the dovetail ends of said shelf.

25 2. In a sectional bookcase, in combination, a base; a top; and an intermediate section comprising a shelf having dovetail ends, two end pieces, a back panel, and a door, the end pieces being connected to the base by means 30 of a tongue-and-groove joint, said joint also providing an undercut channel for receiving the dovetail ends of said shelf.

35 3. In a sectional bookcase, in combination, a base having a tongue projecting upwardly therefrom and two shoulders, one of which is undercut; and a book-section comprising two end pieces and a back panel, each of said end pieces having two tongues at one edge, one of said tongues being undercut to form with said 40 undercut shoulder an undercut groove, and a shelf having a dovetail end adapted to lie within said undercut groove.

45 4. In a sectional bookcase, in combination, a base; a top; a plurality of intermediate sections, each of which sections comprises a shelf, two end pieces and a back panel, each of said end pieces being provided at one edge with two tongues, one of which is undercut, and at its opposite edge with a single tongue and 50 two shoulders, one of which shoulders is undercut, said base being provided with a tongue and two shoulders, one of which shoulders is undercut, and the top being provided with two tongues, one of which tongues is undercut; and an additional shelf for the top of the 55 uppermost section, all of said shelves having dovetail ends.

5. In a sectional bookcase, in combination, a base; a top; a plurality of intermediate sections, each of which sections comprises a shelf, two end pieces and a back panel, each of said end pieces being provided at one edge with two tongues, one of which is undercut, and at its opposite edge with a single tongue and 60 two shoulders, one of which shoulders is undercut, also at its rear edge with a groove for

receiving said back panel, said base being provided with a tongue and two shoulders, one of which shoulders is undercut, and the top being provided with two tongues, one of which tongues is undercut; and an additional shelf for the top of the uppermost section, all of said shelves having dovetail ends and being provided with grooves on their rear edges on both their upper and their lower faces for the reception of said back panels. 70 75

6. In a bookcase, in combination, two end pieces, each having a groove on its inner side near its upper end; a door provided with rollers adapted to move in said grooves, said door 80 having a groove formed near each of its ends on its inner face; and a guide-shoe secured to each of said end pieces, adapted to enter the grooves in said door when said door is moved into a horizontal position. 85

7. A joint for two adjacent members of a knockdown sectional bookcase, which joint comprises a tongue on one of said members, and a shoulder formed on each side of said tongue, and a pair of tongues on the other 90 member forming between them a groove for the reception of said first-mentioned tongue, one tongue of the pair of tongues being adapted to rest upon one of said shoulders, and the other tongue and the other shoulder 95 being undercut to form conjointly the side walls of an undercut groove adapted to receive the dovetail ends of a shelf of the case.

8. A joint for two adjacent side members 100 of a knockdown sectional bookcase and a shelf of said case, which joint comprises a tongue on one of the side members and a shoulder formed on each side of said tongue, a pair of tongues on the other member forming between them a groove for the reception 105 of said first-mentioned tongue, one tongue of the pair of tongues being adapted to rest upon one of said shoulders, and the other tongue and the other shoulder being undercut to form conjointly the side walls of an undercut 110 groove, the ends of said shelf being dovetail to enter said undercut groove. 115

9. A joint for two adjacent members of a knockdown sectional bookcase, which joint comprises a tongue on one of said members, 120 said tongue having a notch near its middle portion and a shoulder formed on each side of said tongue, and a pair of tongues on the other member forming between them a groove for the reception of said first-mentioned tongue, one tongue of said pair of tongues being adapted to rest upon one of said shoulders and the other tongue and the other shoulder being undercut to form conjointly the side walls of an undercut groove, the ends of 125 said shelf being dovetail to enter said undercut groove, also being provided with a pocket, a pin in said undercut shoulder for entering said pocket to hold the shelf in position with relation to the end pieces, and a pin extending 130 between the two tongues of said pair of tongues adapted to enter the notch in said.

single tongue to hold said end pieces in vertical alinement.

10. A door for sectional bookcases, having a mortise-opening formed in one of its ends; a leaf-spring fixed to said door and extending over said opening; a supporting-roller for the door, rotatably mounted at the free end of said leaf-spring; and a similar roller rotatably mounted at the opposite end of said door.
